PULSED HIGH FREQUENCY ELECTRO- THERAPEUTIC UNIT

Carl W. Sundberg, Bloomfield Hills, Mich., assignor to
Diapulse Manufacturing Corp. of America, New York,
N.Y., a corporation of Delaware

Filed Sept. 25, 1959, Ser. No. 57,697

Term of patent 14 years

(Cl. D83—1)

Figure 1 is a front perspective view showing the left side of the pulsed high frequency electrotherapeutic unit embodying my new design, the rear being substantially plain, except for the side arm of I-shaped cross-section which is the same both front and rear, and the stippled shading representing contrasting color; and

Fig. 2 is a front perspective view showing the right side thereof.

The dominant features of my design reside in the full-line portions of the drawing.

I claim:

The ornamental design for a pulsed high frequency electrotherapeutic unit, as shown and described.
